(57) **CLAIM**

The ornamental design for a trunk luggage, as shown and described.

DESCRIPTION

1.1 is a back view of a trunk luggage showing my new design;

1.2 is a bottom view thereof;

1.3 is right side view thereof;

1.4 is a top view thereof;

1.5 is a left side view thereof;

1.6 is a front view thereof; and

1.7 is a front perspective view thereof.

The shading in the drawings reflects areas of color or shading contrast and not particular colors or shadings, and forms no part of the claimed design.
